CARBURETOR

Nick G. La Guardia, Denver, Colo.

Application April 24, 1945, Serial No. 590,043

3 Claims. (Cl. 261—23)

1

This invention relates to new and useful improvements in carburetors such as are employed on motor vehicles, especially the engines of aeroplanes, motor driven boats and automobiles.

The principal object of the present invention is to provide a carburetor which in the instance of an aeroplane will operate to supply fuel to the complementary engines regardless of the position of the engine.

Another important object is to provide a carburetor which under acceleration will function to pump fuel to the atomizer or atomizers of the carburetor.

Still another important object of the invention is to provide a carburetor in which the parts are related in such a manner as to be positive acting and substantially fool-proof at all times.

Other objects and advantages of the invention shall become apparent to the reader of the following description.

In the drawings:

Figure 1 is a side elevational view of the improved carburetor.

Figure 2 is a vertical sectional view taken on line 2—2 of Figure 1.

Figure 3 is a fragmentary vertical sectional view showing a modified form of the invention.

Figure 4 is a fragmentary vertical sectional view showing another form of the invention.

Referring to the drawings wherein like numerals designate like parts, it can be seen that numeral 5 denotes a vertically disposed shell having passageway 6, 7 extending vertically therein and opening through the top thereof. The passageways 6, 7 meet at the point 8 just under a jet 9, which is at the lower end of an intermediate chamber 10. The lower end of the shell 5 is constructed to form a neck 11, flanged, as at 12, for attachment to an intake manifold pipe. The upper end of the shell 5 is flanged, as at 13, for attachment to an air filter (not shown).

In the upper portion of each passageway 6, 7 is a butterfly valve 14, these valves being mounted on a common shaft 15 operated by an arm 16 at one end thereof.

A conduit 17 extends from one side of the shell 5 across the passageway 6, and into the space 18 between the passageways 6, 7 and from there downwardly to communicate with a transverse passageway 19 which at its open ends projects into the passageways 6, 7.

At one side of the shell 5 is provided a bowl 20, having a vertically disposed partition 21 therein, dividing the interior of the bowl into chambers 22 and 23. The bottom of the bowl 22 has a

2

cleanout plug 24, while a fuel inlet connection burr 25 is provided at the upper portion thereof, through which fuel is supplied to the chamber 22. The upper portion of the chamber 22 is formed with a pocket 26, the lower portion of which is covered by a strainer 27.

A float 28 is swingably supported in the chamber 23, as at 29, and has an upstanding member 30 from which projects a needle valve 31 operating against a seat at one end of a port 32 between the pocket 26 and the chamber 23. Thus it can be seen that the floated position of the float 28 in the chamber 23 regulates the admission of fuel to the chamber 23.

15 In the chamber 23 is a formation 33 which has a passageway 34 extending from the face thereof horizontally and then vertically to a valve seat 35 and a pocket 36. The conduit 17 communicates with the pocket 36. A screw valve 37 is feedable through a cover 38 for the bowl 20 and an arm 39 is provided for the upper end of this screw 37. The arm 39 has an opening and a set screw whereby a control cable can be attached thereto.

20 A cylindrical bore 40 is located in the formation 33 and accommodates a piston 41. A rod 42 extends upwardly from the piston 41 and through the cover 38.

A rocker 43 is mounted on the cover 38 and has one end pivoted, as at 44, to the upper end of the piston rod 42, while the other end is adjustably secured, as at 45, to the upper end of a vertical slide rod 46 operating through a vertical guide 47.

25 The lower end of the rod 46 is provided with a head 48 riding a cam 49 located on one end of a horizontal shaft 50 which is disposed through the neck 11 of the shell 5 where it is provided with a butterfly valve 51. The other end of the shaft 50 carries a cam 52 which operates against a rod 53, this rod operating vertically through a guide 54 and being connected by a pivotal link 55, at its upper end to the end of an arm 56 on the outer end of a shaft 57, which carries a butterfly valve 58 within the passageway 17. Compression springs 60 and 61 are provided on the lower portions of the rods 46 and 53.

30 In the lower portion of the formation 33 in the chamber 23 are oppositely opening ball check valves 62, 63. On the upstroke of the piston 41, fuel is sucked into the cylinder 40 from the passageway 34 and on the down stroke, this fuel is forced by way of the check valve 63, to a duct 64 and from there by way of a tube 65 to the chamber 10 in the intermediate portion of the shell 5, this chamber having a jet formation 9 for atomizing fuel into the neck portion 11 under

the pressure of the pump and as air mixes with the same at the junction of the passageways 6, 7. The numeral 68 denotes a small air tube extending from the upper portion of the air passageway 6 to the top of the chamber 23.

Extending from the lower portion of the chamber 23 is an idling fuel supply duct 67 which extends upwardly, as at 68, and then downwardly, as at 69, following the wall of the neck 11, to an outlet 70 in the neck 11 where an adjusting valve 71 is provided.

It can now be seen, that under idling conditions, fuel is supplied from the bowl 23 through the duct 67, 68, 69 to the admission port 70.

However, under acceleration, depending upon the position of the valve 37, fuel is supplied to the point 8 in the shell 5 by way of the duct 34, valve 37, passageway 17 and transverse passageway 18 where it mixes with air rushing down the passageways 6, 7 while at the same time fuel under the pressure of the piston 41 is forced up the duct 64 and by way of the tube 65 into the chamber 10 and atomizes out through the jet 9 to mix at the point 8 with the downwardly rushing roughly mixed air and fuel. Both the piston 41 and the valve 58 are operated by the same manually controlled shaft 50. Obviously, when a sufficient level of fuel has been reached in the chamber 23, the rising of the float 28 actuates the needle valve 31 to shut off the duct 32.

A modification of the invention is shown in Figure 3, this form of the invention showing a shell 5a having passageways 6a, 7a and butterfly valves 14a, 14a in the upper portions thereof located on a common shaft 15a operated by an arm 16a. The shell 5a has a central chamber 18a and inclined conduits 17a, 17a extend across the passageways 6a, 7a and opened to ports 18b formed through the wall of the chamber 18a. Across the shell 5a is disposed a shaft 51a having a butterfly valve 58a operating in the chamber 18a above a pair of jets 19a, 19a terminating in the lower portions of the passageways 6a, 7a. The lower end of the chamber 18a is formed to provide a jet 9a just above the converging point 8a of the passageways 6a, 7a.

In the lower portion of the shell 5a is a neck 11a having an idling fuel port 70a controlled by a screw valve 11a and in the neck 11a just above the idling fuel port 70a is a control valve 51a.

Obviously, when the engine is in operation, air flows down the passageways 6a, 7a, some being bled through the ports 18b, 18b into the chamber 18a to mix with fuel arriving by way of the conduits 17a, 17a. Inasmuch as the fuel entering by way of the passageway 17a is under pressure, the fuel will pass with considerable velocity through the jet 9a and some out of the feed jets 19a, to the end that there will be a complete mixing of the fuel at the junction point 8a.

Figure 4 shows a third modification of the invention wherein the shell 5b has passageways 6b, 7b therein, these passageways having butterfly valves 14b, 14b in the upper portions thereof located on a shaft 15b operated by an arm 16b.

Supported by struts 75 in the passageways 6b, 7b, are Venturi tubes 16, 16 each having a jet 11 projecting into the upper portion thereof with fuel supplied thereto by conduits 18, 18, these conduits extending from a float chamber 23 such as that shown in Figure 2. Butterfly control valves 77 are provided on a common shaft 88 and operated in the portions of the Venturi tubes 16. A jet such as the jet 9 or 9a with the fuel connection to the accelerator pump 40,

such as the connection 65, is located at a junction point equivalent to that of 8 or 8a in Figures 2 and 3 is provided in the lower portion of the shell 5b (not shown).

The carburetor of this invention, therefore, includes two vertically positioned air intake passages coming together at their lower ends to form a common outlet with a butterfly valve in the common outlet and with butterfly valves in their upper inlet ends. A float chamber is positioned at one side of the carburetor and this is provided with a fuel connection and a float with a valve actuated thereby to control the flow of fuel into the float chamber. The carburetor is provided with a connection to supply fuel for idling which extends from the lower end of the float chamber upward in the housing and thence downward to a point in the common outlet beyond the butterfly valve. The main fuel supply is provided through a passage that also extends from the lower end of the float chamber upward to a point midway of the height of the carburetor, and thence into a connection that discharges into the two air intake passages. This fuel supply connection is also provided with a control valve. In addition to the connection for the main supply of fuel and the fuel for idling, the carburetor is also provided with an accelerating cylinder with a piston therein actuated by a cam 15 on the shaft of the butterfly valve in the common outlet and as this cam moves through the operation of the butterfly valve to the extreme position, it forces the piston in the cylinder downward, and in the compression stroke of the piston fuel 20 is forced out of the lower end of the cylinder and through an auxiliary connection to an orifice which forms a jet between the two air intake passages and this auxiliary fuel is ejected into the common outlet. The air intake passages are 25 normally open and unobstructed except for the extending end of the tubular connection 19 which restricts the area in the respective passages at this point slightly, and in Figure 4 the areas of the air intake passages are definitely restricted 30 by the centrally disposed tubes 16 which provide a Venturi action that accelerates the passage of the air therethrough and the fuel is supplied to the air at these constricted points or throats of the passages. The float chamber of the carburetor is also provided with a bleeder connection 35 from the upper end thereof to the upper end of the air intake passages.

While the foregoing specification sets forth the invention in specific terms, it is to be understood that numerous changes in the shape, size and materials may be restored to without departing from the spirit and scope of the invention as claimed hereinafter.

Having described the invention, what is claimed 60 as new is:

1. In a carburetor, the combination, which comprises a housing having a plurality of parallel air intake passages converging to a common outlet, butterfly valves in the intake passages, a butterfly valve in the outlet, a shaft with extending ends having cams on the ends thereof pivotedly mounting said butterfly valve in said common outlet, said housing having a centrally disposed chamber with a discharge orifice in the vertex of a conical-shaped lower end thereof, said orifice aligned with the center of said common outlet, said housing including a float chamber extending at one side of said intake passages and intermediate the ends thereof, a fuel supply connection communicating with the interior of

the float chamber, a float in said float chamber, a valve in said fuel supply connection actuated by said float, said float chamber having an inner cylinder therein, a piston in said inner cylinder, levers actuated by one of the cams on the butterfly valve shaft to operate the piston in a compression stroke thereof, means resiliently returning the piston, check valves in the cylinder in the float chamber admitting fluid to the cylinder in the returning stroke of the piston and providing release of fluid in the cylinder through a connection to the vertex of said centrally disposed chamber of the housing as the piston is actuated through the compression stroke, said housing having a fluid supply connection from the lower end of the float chamber to the valve intake passages thereof, a control valve in said connection, a butterfly valve in said fluid supply connection, means actuating the butterfly valve in said fluid supply connection by one of the cams on said butterfly valve shaft, said housing having a passage for fuel for idling extending from the lower end of the float chamber upward to a point midway of the height of the housing and thence downward to a point in the common outlet beyond the butterfly valve therein, and a control valve in said idling fuel passage.

2. In a carburetor, the combination, which comprises a housing having a plurality of parallel air intake passages having constricted areas intermediate their ends providing Venturi action therein, said passages converging to form a common outlet, butterfly valves in the intake passages, a butterfly valve in the common outlet, a shaft with extending ends having cams on said ends pivotally mounting said butterfly valve in said common outlet, said housing having a centrally disposed chamber having a discharge orifice in the vertex of a conical-shaped lower end thereof, said orifice aligned with the center of said common outlet, said housing including a float chamber extending at one side of said intake passages and intermediate the ends thereof, said housing also having a fuel supply connection communicating with the interior of the float chamber, a float in said float chamber, a valve in said fuel supply connection actuated by said float, said float chamber having an inner cylinder therein, a piston in said inner cylinder, levers actuated by one of the cams on the butterfly valve shaft to operate the piston through a compression stroke thereof, means resiliently returning the piston, check valves in the cylinders admitting fluid to the cylinder in the returning stroke of the piston and providing release of fluid in the cylinder through a connection to the vertex of said centrally disposed chamber of the housing in the compression stroke of the piston therein, said housing having a fluid supply connection from the float chamber to the constricted area of the air intake passages, a control valve in said connection, a butterfly valve in said fluid supply connection, means actuating the butterfly valve in the fluid supply connection as the butterfly valve in the common outlet is actuated, said housing having a passage for fuel for idling extending from the lower end of the float chamber upward to a point midway of the height of the housing and thence downward to a point in the common outlet beyond the butterfly valve therein, a control valve in said idling fuel passage, and a connection from the upper end of the float chamber to the upper end of the housing above the butterfly valve therein communicating with said intake passages.

way of the height of the housing and thence downward to a point in the common outlet beyond the butterfly valve therein, and a control valve in said idling fuel passage.

- 5 3. In a carburetor, the combination, which comprises a housing having a plurality of parallel air intake passages having constricted areas intermediate their ends providing Venturi action therein, said passages converging to form a common outlet, butterfly valves in the intake passages, a butterfly valve in the common outlet, a shaft with extending ends having cams on said ends pivotally mounting said butterfly valve in said common outlet, said housing having a centrally disposed chamber having a discharge orifice in the vertex of a conical-shaped lower end thereof, said orifice aligned with the center of said common outlet, said housing including a float chamber extending at one side of said intake passages and intermediate the ends thereof, said housing also having a fuel supply connection communicating with the interior of the float chamber, a float in said float chamber, a valve in said fuel supply connection actuated by said float, said float chamber having an inner cylinder therein, a piston in said inner cylinder, levers actuated by one of the cams on the butterfly valve shaft to operate the piston through a compression stroke thereof, means resiliently returning the piston, check valves in the cylinders admitting fluid to the cylinder in the returning stroke of the piston and providing release of fluid in the cylinder through a connection to the vertex of said centrally disposed chamber of the housing in the compression stroke of the piston therein, said housing having a fluid supply connection from the float chamber to the constricted area of the air intake passages, a control valve in said connection, a butterfly valve in said fluid supply connection, means actuating the butterfly valve in the fluid supply connection as the butterfly valve in the common outlet is actuated, said housing having a passage for fuel for idling extending from the lower end of the float chamber upward to a point midway of the height of the housing and thence downward to a point in the common outlet beyond the butterfly valve therein, a control valve in said idling fuel passage, and a connection from the upper end of the float chamber to the upper end of the housing above the butterfly valve therein communicating with said intake passages.
